UNITED STATES PATENT OFFICE

142,255

DESIGN FOR A STRAINING FUNNEL COMBINATION UNIT

Ray T. Frost, West Hollywood, Calif., assignor to
Plas-Tex Corporation, West Hollywood, Calif.,
a corporation of California

Application October 5, 1944, Serial No. 115,625

Term of patent 7 years

(Cl. D44—29)

To all whom it may concern:

Be it known that I, Ray T. Frost, a citizen of the United States, residing at West Hollywood, in the county of Los Angeles and State of California, have invented a new, original, and ornamental Design for a Straining Funnel Combination Unit, of which the following is a specification, reference being had to the accompanying drawings, forming part thereof.

Fig. 1 is a plan view of a straining funnel combination unit sieve showing some of the several inserts broken away.

Fig. 2 is an elevation of the combination sieve shown in Fig. 1.

Fig. 3 is an exploded view in perspective showing the individual sieve units which make up the combination unit shown in Fig. 2.

I claim:

The ornamental design for a straining funnel combination unit, substantially as shown.

RAY T. FROST.
